UNITED STATES PATENT OFFICE.

ABRAHAM SCHWARTZMAN, OF ST. LOUIS, MISSOURI.

JEWELEY.

1,189,497.

Specification of Letters Patent.

Patented July 4, 1916.

Application filed September 13, 1915. Serial No. 50,474.

To all whom it may concern:

Be it known that I, ABRAHAM SCHWARTZMAN, a citizen of the United States, residing at the city of St. Louis, State of Missouri, have invented a certain new and useful Improvement in Jewelry, of which the following is a specification, reference being had to the accompanying drawing, forming a part thereof.

10 This invention relates generally to jewelry and, more particularly, to a certain new and useful article of jewelry especially adapted and designed for use as a chain, necklace, bracelet, or the like, the principal 15 object of my present invention being to provide an attractive and ornamental article of jewelry of the kind and for the purposes stated made up of or comprising a plurality or series of flexibly and detachably connected neat and artistic members each preferably set with a precious or semi-precious stone or other jewel.

With the above and other objects in view, my invention resides in the provision of an 25 article of jewelry capable of being used for a variety of purposes; in the means for connecting the individual members or pieces of the jewelry, said means being of such form as to provide a simple and effective 30 universal joint, thereby permitting freedom of movement of the pieces or members in all directions with respect to one another; in the provision of an article of jewelry which, by virtue of its sectional construction, may 35 be readily and conveniently lengthened or shortened as desired and to suit different requirements; and in the novel features of form, construction, arrangement, and combination of the several parts of the jewelry, 40 all as hereinafter described and afterward pointed out in the claims.

In the accompanying drawing, which illustrates my new jewelry in preferred form, Figure 1 is a plan view of an article 45 of jewelry embodying my invention, the same being shown as a necklace; Fig. 2 is an inverted plan view of a connected series of the sections or members of which my new article of jewelry is formed; Fig. 3 is a side 50 elevational view of the same; Fig. 4 is an enlarged inverted plan view of a connected pair of said members or sections, portions thereof being in section; and Fig. 5 is an enlarged side elevational view of one of 55 said sections or members, the same being op-

eratively connected or attached to another of said sections or members shown in vertical section.

Referring to the said drawing, in which like reference characters refer to like parts throughout the several views, each section or member of my new jewelry is preferably of skeleton form and comprises a front ring 10 and a rear ring 11, the same being preferably equal in size or diameter and composed of any suitable metal, either solid or plated. Rings 10 and 11 are laterally spaced a suitable distance apart and united by short posts or cross-pieces 12, which latter are annularly spaced at suitable distances apart, not only to reduce the weight of the member, but also to provide apertures or slots, as at 12^a, therebetween. Posts 12 may be formed integrally with the rings 10 and 11 or rigidly fixed thereto in any suitable manner, as may be desired.

Concentrically arranged within front ring 10 is a ring 13, and centrally arranged in ring 13 is a jewel cup 14 adapted to receive a stone or other jewel 15, cup 14 being provided with suitable prongs 16 to engage over the edge of the stone or jewel, as will be well understood. Extending from cup 14 to outer ring 10 and intersecting inner ring 13 are radially disposed arms or members 17.

In order to give the best effect to the stone or other jewel 15 carried by the skeleton member of the jewelry, I prefer to form said member with the top of the cup 14 and its prongs 16 so that the same occupy a plane slightly above the plane occupied by the front face of inner ring 13 and with the front face of ring 13 a slight distance above the front face of outer ring 10. This arrangement presents a neat and finished appearance and materially elevates the stone or other jewel with respect to the front face of the skeleton member. If desired, the front faces of rings 10 and 13 may be suitably 95 ornamented by engraving or the like.

The means utilized and provided by me for operatively connecting the several skeleton members or sections of my new jewelry comprises substantially flat metal shanks 18 and 19, the same loosely occupying a corresponding pair of apertures or slots 12^a formed or provided, as described, in the sides of an adjacent pair of the said skeleton members or sections. It will be understood 100

100

105

110

that shanks 18 and 19 are substantially smaller than the apertures or slots 12^a through which they pass, being thus free to move through said apertures for a limited distance substantially in all directions laterally and longitudinally relatively to the skeleton members or sections.

Formed integrally with, or suitably fixed to, the outer ends of shanks 18 and 19 are heads or cross-pieces 20 preferably curved slightly throughout their length to conform to the curvature of the inner faces of the corresponding rings 10 and 11. Heads or cross-pieces 20 are substantially longer than the slots or apertures 12^a through which the shanks 18 and 19 project, thus preventing said shanks from withdrawing from the sectional members of the jewelry.

At its outer end, shank 18 is suitably bifurcated to provide a pair of spaced ears 21, which are suitably perforated to receive a screw or the like 22, the perforation through one of said ears being threaded, as illustrated in Fig. 4. The corresponding end of shank 19 is provided with a perforated head 23 adapted to occupy a position between the ears 21, the screw or the like 22 being removably seated in the apertures or perforations of said ears 21 and head 23 to detachably secure the said members or sections of the jewelry together. This construction forms a hinge-joint between the shanks 18 and 19, which joint, together with the loose connections between the shanks and the slots or apertures through which the same pass, not only readily permit the connected members of the jewelry to swing freely in all directions with respect to one another, but at the same time also forms a substantial tie or connection between said members.

When it is desired to utilize a few of the connected sections or members as a necklace, as illustrated particularly in Fig. 1, the shanks which project outwardly from the outer pair of members are provided with detachable links 24 having loops 25 which preferably extend upward, these loops 25 serving as points of attachment for the ends of a chain 26 adapted to encircle the neck of the wearer.

Jewelry of my invention is adapted for a wide variety of uses and, by reason of the detachable universal joint members which serve as connectors between the several individual members or sections, is not only flexible to a marked degree, but may be readily lengthened or shortened to suit individual tastes or requirements.

It will be readily understood that the several members of my new jewelry article may be made in various shapes and sizes and ornamented as desired, and that other changes in the size, form, construction, arrangement, and combination of the various parts of my new jewelry may be made and substituted for

those herein shown and described without departing from the nature and principle of my invention.

Having thus described my invention, what I claim and desire to secure by Letters Patent is:

1. As a new article of manufacture, jewelry comprising a pair of members, and means including a pair of lengthwise rigid pivotally-connected shanks having loose engagement with said members for flexibly connecting said members together, said shanks while engaging said members being freely pivotally movable relatively to each other and movable longitudinally relatively to said members.

2. As a new article of manufacture, jewelry comprising a pair of members, and means including a pair of lengthwise rigid pivotally connected shanks having loose engagement with said members for flexibly connecting said members together, said shanks while engaging said members being freely pivotally movable relatively to each other and laterally movable relatively.

3. As a new article of manufacture, jewelry comprising a pair of members, and means including a pair of lengthwise rigid pivotally connected shanks having loose engagement with said members for flexibly connecting said members together, said shanks while engaging said members being freely pivotally movable relatively to each other and laterally and longitudinally movable relatively to said members.

4. As a new article of manufacture, jewelry comprising a pair of slotted members, and means including a pair of pivotally connected shanks loosely projecting through slots in said members for flexibly connecting said members together, said shanks while projecting through said slots being movable longitudinally and laterally relatively to said members.

5. As a new article of manufacture, jewelry comprising a pair of slotted members, and means for flexibly connecting said members together, said means including a pair of pivotally connected shanks having loose engagement with, and loosely projecting through slots in, said members.

6. As a new article of manufacture, jewelry comprising a pair of slotted members, and means for flexibly connecting said members together, said means including a pair of pivotally connected shanks loosely projecting through slots of said members, and heads on said shanks within said members, said heads being adapted to loosely engage with said members to prevent withdrawal of said shanks from said slots.

7. As a new article of manufacture, jewelry comprising a pair of slotted members, and detachable means for flexibly connecting said members together, said means in-

- cluding a headed shank loosely engaging with, and projecting through the slot of, one of said members, the outer end of said shank being bifurcated, a second headed shank 6 loosely engaging with, and projecting through the slot of, the other of said members, the outer end of said second shank being adapted to fit the bifurcated end of said first shank, and a pin removably seated 10 in the outer ends of said shanks for detachably pivotally connecting said shanks together.
8. As a new article of manufacture, jewelry comprising a pair of slotted members, 15 each of said members including a pair of connected rings spaced apart, and means for flexibly connecting said members together, said means including a pair of pivotally connected shanks loosely projecting through 20 slots of said members, and heads on said shanks within said members and adapted to loosely engage therewith to prevent withdrawal of said shanks from said slots, said heads being lengthwise curved to correspond with the curvature of the inner faces 25 of said rings.
9. As a new article of manufacture, jewelry comprising a pair of members, each of said members including a pair of laterally spaced apart rings and posts extending between and uniting said rings together, said posts being annularly spaced apart and thereby providing slots between said rings, and means for flexibly connecting said members together, said means including a pair of pivotally connected shanks loosely projecting through slots of said members, and heads on said shanks within said members, 30 35 40 45 50 55 60 65 70
- said heads being adapted to engage with posts of said members to prevent withdrawal of said shanks from said members.
10. As a new article of manufacture, a jewelry article comprising a pair of laterally spaced apart rings, and annularly spaced apart posts extending between and fixed to said rings for uniting the same rigidly together, said posts and the spaces therebetween being adapted also for the reception of, and engagement with, connecting-members, as described.
11. As a new article of manufacture, a jewelry article comprising a shank having a lengthwise curved head at one end, the other end of said shank being bifurcated, a second shank also having a lengthwise curved head at one end, the other end of said second shank being adapted to fit the bifurcated end of said first shank, and a pin engaging the meeting ends of said shanks for pivotally fastening said shanks together.
12. As a new article of manufacture, jewelry comprising an annular slotted member, a shank loosely projecting through the slot of said member and movable in said slot relatively to the member, and a head on said shank within the member, said head being lengthwise curved to correspond with the curvature of said member and being adapted to loosely engage with said member to prevent withdrawal of the shank from said slot.

In testimony whereof, I have signed my name to this specification.

ABRAHAM SCHWARTZMAN.
